Walter Raskin, Orange, N. J.

Application September 22, 1944, Serial No. 115,406

Term of patent 7 years

(Cl. D80—11)

To all whom it may concern:

Be it known that I, Walter Raskin, a citizen of the United States of America, residing in the city of Orange, county of Essex, and State of New Jersey, have invented a new, original, and ornamental Design for a Display Cabinet or Similar Article, of which the following is a specification, reference being had to the accompanying drawings forming a part thereof.

In the drawings:

I claim:

The ornamental design for a display cabinet or similar article, as shown.

WALTER RASKIN.
